UNITED STATES PATENT OFFICE

WILLIAM C. CANDLISH, OF BERKELEY, CALIFORNIA, ASSIGNOR TO J. R. PALMEN-BERG'S SONS, INC., OF NEW YORK, N. Y.

DESIGN FOR A PEDESTAL FOR DISPLAY FIXTURES

Application filed July 1, 1929. Serial No. 31,920. Term of patent 7 years.

to all whom it may concern:

Be it known that I, WILLIAM C. CANDLISH, citizen of the United States, residing at Berkeley, in the county of Alameda and state of California, have invented a new, original, and ornamental Design for a pedestal for Display Fixtures, of which the following is a specification, reference being had to the accompanying drawing, forming part thereof.

I claim:

The ornamental design for a pedestal for display fixtures as shown.

WILLIAM C. CANDLISH.
